UNITED STATES PATENT OFFICE

103,823

DESIGN FOR A BOTTLE

Marcelle Harris Lowenstein, Atlanta, Ga.

Application December 30, 1936, Serial No. 66,816

Term of patent 3½ years

To all whom it may concern:

Be it known that I, Marcelle Harris Lowenstein, a citizen of the United States, residing at Atlanta, in the county of Fulton, State of Georgia, have invented a new, original, and ornamental Design for a Bottle, of which the following is a specification, reference being had to the accompanying drawing, forming part thereof.

The figure is a face view of the bottle, round in cross-section, showing my new design.

I claim:

The ornamental design for a bottle, as shown and described.

MARCELLE HARRIS LOWENSTEIN.
